UNITED STATES PATENT OFFICE.

GEORGE H. COOPER, OF NEW WESTMINSTER, CANADA.

AIR-MOTOR.

SPECIFICATION forming part of Letters Patent No. 593,923, dated November 16, 1897.

Application filed April 14, 1897. Serial No. 632,101. (No model.)

To all whom it may concern:

Be it known that I, GEORGE H. COOPER, of New Westminster, Province of British Columbia, Dominion of Canada, have invented a new and useful Improvement in Air-Motors, of which the following is a full, clear, and exact description.

My invention relates to air-motors, particularly such as are employed for propelling street-cars.

The object of my invention is to provide an air-motor in which a compound effect may be obtained, the air being used at the same pressure it has in the reservoir. Provision is also made for applying air under the same pressure to two or more pistons after the pressure in the reservoir has fallen so much as to render a compound effect impracticable or uneconomic.

Another object of my invention is to utilize the surplus power not required for propulsion to operate a compressor for the purpose of partly replenishing the supply of air in the reservoir. I also provide improved means for governing the speed of the motor. The compressor above referred to also forms a very efficient brake.

The features of construction whereby the above-indicated results are obtained will be fully described hereinafter and the novelty pointed out in the appended claim.

Reference is to be had to the accompanying drawing, which is a longitudinal section of an air-motor constructed according to my invention.

A is the supply-pipe connected to the air-reservoir. (Not shown.)

B is a throttle-valve or other suitable valve located in the supply-pipe, said valve being operated to start or stop the motor.

The supply-pipe A leads to the chest C, in which moves the slide-valve D of the high-pressure cylinder E, having inlet-ports E' and an exhaust-port E² substantially like those of an ordinary steam-engine. The exhaust-port E² is connected by a pipe or channel F to the chest C' of the slide-valve D', controlling the admission of air to the second or medium-pressure cylinder E⁴. This cylinder is of larger diameter than the high-pressure cylinder E. The exhaust-port E⁵ of the second cylinder is connected by a channel or pipe F'

to the valve-chest C² of the third or low-pressure cylinder E⁶, in which slides the valve D². The slide-valves D D' D² are operated in unison, their rods G G' G² being connected to the valve-gear in any suitable manner.

In the cylinders E E⁴ E⁶ are arranged the pistons H H' H², secured to a common piston-rod I, which is connected to the driving mechanism in any approved manner. On said rod is also secured a piston H³, working in the cylinder J of an air-compressor, said compressor having ports K K' at its upper end, which ports are connected by means of pipes L to the supply-pipe A at a point between the reservoir and the valve B. The pipes L have outwardly-opening check-valves M. Between said valves and the ports K K' the pipes L are connected to branch pipes N, having inwardly-opening check-valves O, and the two pipes N are connected into one, as shown at N', their connection with the atmosphere being controlled by a valve P, placed within ready reach of the operator. The supply-pipe A is also directly connected to the slide-valve chests C' and C² of the medium-pressure and low-pressure cylinders E⁴ and E⁶, respectively, the connection being effected by means of pipes Q and controlled by valves Q', so that the compressed air may be admitted to the cylinders E⁴ and E⁶ directly from the supply-pipe A, if desired.

The operation of my air-motor is as follows: The valve B being opened and the valves Q' closed, air is admitted to the high-pressure cylinder E under the same pressure it has in the reservoir. The air operates the piston H in the well-known manner and then escapes through the pipe F to the medium-pressure cylinder E⁴, where it operates the piston H' and finally travels in a like manner through the pipe F' into the low-pressure cylinder E⁶, whence it escapes to the atmosphere after actuating the piston H². The reciprocating piston-rod I actuates the piston H³ of the compressor, forcing the air from the cylinder J at each stroke through one of the pipes L to the air-reservoir. At each stroke air is drawn into the cylinder J through one of the pipes N, and by opening the valve P more or less the operator can control the resistance opposed to the motion of the piston H³ and thereby regulate the speed of the car.

It will be understood that the compressor is operated only by the excess of power above that required for propulsion. The compressor will act as a brake, particularly on a down-grade, and will, moreover, partly replenish the supply of air in the reservoir.

It will be evident that the air is used expansively in the cylinders E⁴ and E⁶, the motor shown being thus a triple-expansion motor. The same construction could of course be applied as well to a motor having two, four, or more cylinders receiving the air successively.

When the pressure in the reservoir becomes so low that little or no power is obtained by expansion in the low-pressure cylinder E⁶, I open the valve Q', leading to the medium-pressure cylinder E⁴, so that the piston H' (of larger area than the piston H) becomes the high-pressure piston and only the cylinder E⁶ is a compound cylinder. After a further reduction of pressure in the reservoir air may be admitted directly to the largest cylinder E⁶.

The advantages of my improved motor are an economic utilization of the air at the res-

ervoir-pressure, dispensing with a reducing-valve, an easy control of the speed, a powerful braking action, the change from compound to direct action as the pressure falls in the reservoir, and the partial replenishing of the air-supply. By connecting the pipe L to the supply-pipe A instead of directly to the reservoir I secure the advantage that the heated air from the compressor enters the motor-cylinders first, and thus prevents the formation of ice.

Having thus described my invention, I claim as new and desire to secure by Letters Patent—

An air-motor having a cylinder and a piston therein, an air-supply channel connected to said cylinder, a compressor operated by said piston, and a valved compressed air-channel leading from said compressor directly to the air-supply pipe to partly replenish the supply of air, substantially as described.

GEORGE H. COOPER.
